United States Patent Office

Des. 208,786
Patented Oct. 3, 1967

208,786

DOLL

Shigehiko Imahori, Nagoya, Japan, assignor to Parksmith Corporation, New York, N.Y., a corporation of New York

Filed Nov. 29, 1966, Ser. No. 4,851

Term of patent 14 years

(Cl. D34—4)

FIG. 1

FIG. 2

FIG. 1 is a front elevational view of a doll, showing my new design; and

FIG. 2 is a side elevational view of said doll.

The dominant features of my design reside in the full line portions shown.

I claim:

The ornamental design for a doll, substantially as shown and described.
